(57) **CLAIM**

The ornamental design for an audio headset, as shown and described.

DESCRIPTION

FIG. 1 is a bottom view of an audio headset; FIG. 2 is a top view of the audio headset of FIG. 1; FIG. 3 is a front view of the audio headset of FIG. 1; and, FIG. 4 is a back view of the audio headset of FIG. 1. The exterior faces of the audio headset's earcups, as shown in FIGS. 1-4 form no part of the claimed design.

1 Claim, 3 Drawing Sheets(56)
